J. SCHMADEL.

Domestic Boiler.

No. 21,702.

Patented Oct. 5, 1858.

UNITED STATES PATENT OFFICE.

JOSEPH SCHMADEL, OF DAYTON, OHIO.

COOKING-BOILER FOR RANGES AND STOVES.

Specification of Letters Patent No. 21,702, dated October 5, 1858.

To all whom it may concern:

Be it known that I, JOSEPH SCHMADEL, of Dayton, in the county of Montgomery and State of Ohio, have invented a new and useful Improvement in Cooking Vessels and Boilers for Stoves or Ranges; and I do hereby declare that the following is a full, clear, and exact description of the same, reference being had to the annexed drawings, making 10 a part of this specification, in which—

Figure 1, is a vertical section of my invention taken in the line x, x , Fig. 2. Fig. 2, is a horizontal section of do, taken in the line y, y , Fig. 1.

15 Similar letters of reference indicate corresponding parts in the two figures.

This invention consists in having the lower part of a boiler, kettle, or other vessel provided with a series of tubes placed 20 around the vessel at its inner side and communicating with the fire when the vessel is placed on the stove or range, the upper ends of the tubes communicating with a chamber which encompasses the upper part of the 25 vessel, said chamber being connected with the flue or pipe and formed by having the upper part of the vessel constructed with double sides.

By this invention the draft of the fire is 30 made to pass through the tubes and chamber of the vessel and the fire and heated products of combustion brought more directly in contact than usual with the contents of the vessel, thereby expediting the heating or 35 cooking of the same and effecting a saving both in time and fuel.

To enable those skilled in the art to fully understand and construct my invention I will proceed to describe it.

40 A, represents a wash boiler or a cooking vessel which may be constructed of sheet metal and externally it may be of any of the known forms. Within the lower part of the boiler A, a series of tubes a , are placed, the 45 lower ends of which pass through to the bottom b , of the boiler and are open at their

lower ends, the ends or orifices of the tubes being flush with the external surface of the bottom b , as shown clearly in Fig. 1.

Around the upper part of the vessel A, a 50 chamber c , is formed. This chamber is obtained by having the upper part of the vessel constructed with double walls d, d , and the upper ends of the tubes a , communicate with the chamber c , as shown at e . 55 The chamber c is connected with a pipe f , which communicates with the smoke pipe g , both pipes being provided with dampers h, h' .

When the boiler A, is placed on the stove 60 or range B, and the damper h' , in the pipe g , closed, and the damper h , in the pipe f , opened, the entire blast from the fire will be compelled to pass through the tubes a, a , and around the boiler so as to heat it very 65 quick with very little fuel, and then pass through the pipe f , into the pipe g . When the blast from the fire is no longer needed around the boiler the damper h' , may be opened and the damper h , closed, and the 70 blast of the fire applied to heat an oven or for other purposes.

It will be apparent that my new boiler will be heated much quicker, with far less fuel, and in far less time, than if the fire 75 only came in contact with that portion of the boiler which projects below the top of the stove or range.

Having described my invention, I claim—

The new manufacture of cooking boiler 80 for stoves and ranges described, to wit, a cooking boiler provided with perpendicular tubes or flues around its sides, from the bottom upward and opening into a horizontal flue or chamber around the top of the boiler, 85 for the blaze and smoke to pass through substantially as described.

JOSEPH SCHMADEL.
